ATTORNEY.

UNITED STATES PATENT OFFICE.

JOHN S. HULL, OF BALTIMORE, MARYLAND.

SOLDERING-IRON.

SPECIFICATION forming part of Letters Patent No. 248,321, dated October 18, 1881.

Application filed August 1, 1881. (No model.) Patented in England March 4, 1879.

To all whom it may concern:

Be it known that I, JOHN S. HULL, of Baltimore city, State of Maryland, have invented certain new and useful Improvements in Soldering-Irons; and I hereby declare the same to be fully, clearly, and exactly described, as follows, reference being had to the accompanying drawings, in which—

Figure 1 is a side elevation of the device complete. Fig. 2 is a similar view of a modified form of the lower part of the same; and Fig. 3 is a side elevation, on a somewhat enlarged scale, of the iron and solder feeder.

My invention has for its object to provide a heater for the soldering-irons used in capping provision-cans, whereby the iron may be kept at the desired temperature for an indefinite time, and the loss of time and material, which is mainly attributable to inefficient capping as at present practiced may be avoided.

The conventional "capping-iron" consists of a copper soldering-tool removably mounted in a suitable holder through which passes the center rod. The iron being heated the point of the rod is stepped in the central indentation of the can-cap, and the iron is twirled about the rod after the manner of a pair of dividers, its point running in the cap-groove and melting the solder which was previously placed there. The iron soon cools off and must be reheated, its place being taken by a second iron, which was heating pending the use of the first.

I would here state that I am aware that it is not new, broadly, to maintain a flame upon a soldering-iron pending its use, as various devices are known in which a gas-jet is made to play upon the iron, and in others gasoline is used; but none of them have superseded the old "center-rod iron" and fire-pot, which is almost universally used in the large canning establishments.

The work done by the common iron is necessarily anything but uniform, the iron being liable, when first taken from the fire-pot and nearly red hot, to "burn" the solder and cause blow-holes by reason of the evolution of steam from the contents of the can, and when the iron is nearly cooled off the fact is only made apparent by the inefficiency of its work. An antecedent and undetected defect becomes apparent when the cap blows off in the "process" vat. These defects are obviated by the device form-

ing the subject of my present invention. I maintain the iron at a uniform temperature, and afford facility for the operation of capping by means of certain features of construction that are hereinafter fully described and made the subject of the claims.

In the drawings, A is the handle, and B the reservoir, constructed of stout sheet metal, and having a suitable orifice, *a'*, through which gasoline or equivalent volatile hydrocarbon may be supplied to the reservoir, and with which a suitable condensing air-pump may be made to communicate.

Into the base *a* of the reservoir the center rod, *b*, is screwed, and transversely through the bottom of the reservoir is screwed the supply-pipe *H* of the burner. This pipe is laterally perforated at *h* for the entrance of the gasoline, and being threaded externally the burner may be adjusted to or from the iron, as may be desired.

Into the chamber I of the burner passes the valve-rod *i*, by means of which the flow of gasoline may be regulated. The jet-tube *i'* is the usual laterally-perforated Bunsen pipe, and is bent at right angles, in order to deliver the blast horizontally against the iron near its point.

For a more particular description of the burner see my patent of April 20, 1880, No. 226,753.

The soldering-iron *c* is a copper bar having its lower end curved to conform to the cap-seam, and is held in a block, *C*, by means of a set-screw, *c'*, so that it may be fed down as it wears away. The block *C* is bifurcated, so as to embrace the rod *b*, and is slotted, as shown, for the passage of the pivot-screw *E*.

Through the rod *b* passes a bar, *F*, having a curved guide, *G*, on its end through the slot, in which passes a pin, *g*, that connects the ends of the part *C*. The bar *F* is secured in the rod *b* by a screw, *f*. By these means the iron is maintained at a constant distance from the rod *b*, but is free to rise and fall as it encounters any roughness in the seam. As an alternative for this construction I may use that shown in Fig. 2, in which the block *C* is pivoted at *l'* to a bar, *L*, which latter passes through a block, *m*, on the rod *b*, and is secured by a set-screw, *l*. In either case the point of the iron is free to tilt upward, and the iron may be adjusted bodily to or from the rod by loosening the screws

l or *f* and pushing the bars *F* or *L* in or out as desired.

To the side of the block *C* is attached a block, *n*, through which passes a funnel-shaped tube, *D*, secured by a screw, *d*. The lower end of this tube is nearly in contact with the iron, as shown.

In operation the burner is ignited and the iron heated to the required temperature. The 10 point of the center rod is then placed in the indentation of the can-cap, and a piece of solder is thrown into the tube *D*. The device, including the center rod, is then rotated, the end of the rod constituting the pivot, and the iron 15 traverses the cap-seam and spreads the solder, which, meanwhile, melts and flows out upon the seam.

Instead of applying the solder through the tube *D* the device may be used in the ordinary 20 way with segment-solder or drop-solder laid in the cap-groove.

The reservoir *B* may be made large enough to hold a quantity of gasoline sufficient for a whole day's work, as the heat being constantly 25 supplied to the iron a very small jet keeps it amply hot enough.

The handle *A* serves as a reservoir for compressed air, and is furnished with a spring-seated valve, *a'*, to relieve any undue pressure caused by the volatilization of the gasoline.

To protect the reservoir from the heat a shield, *M*, is made to surround its base.

The device is most efficient and satisfactory in operation, its efficiency being mainly due to the fact that the iron is kept at a constant temperature.

The subject-matter of the annexed claims 1 and 2 is patented to me in British Letters Patent, dated March 4, 1879, sealed May 9, 1879.

What I claim as new, and desire to secure by 40 Letters Patent, is—

1. In a soldering-iron, a gasoline-reservoir surmounted by a chamber for compressed air, a pivot-rod attached to the end of the reservoir, a soldering-iron located at one side of the 45 rod and parallel therewith, and a self-generating burner having rigid communication with the reservoir, arranged and operating substantially as set forth.

2. In a soldering-iron, a gasoline-chamber 50 surmounted by an air-chamber substantially cylindrical in cross-section and constituting a handle for revolving the device, a central pivotal rod projecting from the base of the reservoir, a soldering-iron parallel with the rod, 55 and a self-generating burner having rigid communication with the reservoir, the parts being combined and operating as set forth.

3. In combination with the reservoir for air and gasoline, the central pivot-rod and self-generating burner having rigid communication with the reservoir, a soldering-iron intermediate the burner and rod and susceptible of a free rising and falling motion, as set forth.

4. In combination with the pivot rod and 65 handle, the soldering-iron and slotted bars *C* and *F*, pivot-pin *E*, and pin *g*, as set forth.

5. In combination with the reservoir and hollow handle, the pivot-rod, burner, and soldering-iron, the solder-duct *D*, and means of supporting the soldering-iron and duct from the 70 pivot-rod, as set forth.

JOHN S. HULL.
